UNITED STATES PATENT OFFICE

RALPH M. HARDGROVE, OF BETHLEHEM, PENNSYLVANIA, ASSIGNOR TO FULLER-LEHIGH COMPANY, OF FULLERTON, PENNSYLVANIA, A CORPORATION OF DELAWARE

GRINDING MILL

Application filed May 14, 1928. Serial No. 277,437.

This invention relates to a device for grinding or pulverizing particles of solid material such as lumps of coal, for example, by means of balls rolling along grinding surfaces. The fine particles of material produced by the grinding operation may be removed by an air current or other means.

Heretofore it has been customary to drive grinding balls in grinding mills of certain types by means of pressure or pusher arms that revolve around a central axis. In such devices, the tendency is for the balls to wear barrel-shaped, and the pressure arms also wear away rapidly. When the balls have been worn to irregular shapes, they are apt to slide around upon the grinding surfaces, thereby causing the same to wear even more rapidly without grinding the material efficiently.

By the present invention, grinding balls are carried around by means of a rotating table, so that all parts of the surfaces of the balls come into contact with the table and grinding ring, thus causing the balls to wear evenly and also decreasing the amount of power necessary to drive the balls.

The invention will be understood from the description in connection with the accompanying drawings, in which Fig. 1 is a side view, partly in section, showing an illustrative embodiment of the invention; Fig. 2 is a vertical section on an enlarged scale, partly broken away, showing some of the details; Fig. 3 is a vertical section, partly broken away, showing a modification; Fig. 4 is a vertical section on an enlarged scale, partly broken away, showing some of the details of the modification, and taken along the line 4-4 of Fig. 5; Fig. 5 is a plan view of Fig. 4; Fig. 6 is a vertical section on an enlarged scale, partly broken away, showing some of the details of a further modification; and Fig. 7 is a plan view of Fig. 6.

In the drawings, reference character 1 indicates a grinding mill that is provided with a device 2 for feeding coal or other material into the mill to be ground. This feeder 2 may be driven by motor or in any other convenient manner, and may be regulated so as to introduce the material into the mill at the

proper rate. An air inlet 3 for forced air enters one side of the casing and the air therefrom passes under the lower edge of the baffle 4 and thence out through the outlet 5 at the top, picking up the fine particles of ground material and carrying them away.

A grinding ring 6 is provided near the bottom of the mill and is retained in place by means of the outside ring or holding member 7. The grinding balls 8 are rolled around in contact with the grinding ring 6 in the manner described below.

A vertical shaft 9 is provided at the lower end of the mill and is mounted in a bearing 10 on the spider 11 that is attached to the base 12 of the machine by bolts, or in any other convenient manner. A stuffing box or packing ring 13 surrounds the shaft 9 above the bearing 10 to prevent dust from entering the bearing. The upper end of the shaft 9 is made conical as shown at 14, to provide a seat for a ball supporting member or table 15 that is kept in place by means of the nut 16 on the shaft 9. The table 15 may be provided with a replaceable wearing ring 17 whose outer or ball contacting surface 18 may be hardened to withstand wear. Plows 19 may be attached to the edge of the table and extend into the space beneath the balls 8 to prevent the material from packing within this space.

A gear 20 is mounted on the shaft 9 below the table 15 and drives the shaft. A pinion 24 on the shaft 25 of the motor 26 drives the gear 20.

In the modification shown in Figs. 6 and 7, the balls 8 are shown as being of different sizes and the other parts are similar to those already described.

The operation is as follows: The material to be ground is fed into the machine by the feeder 2, and the air entering through the inlet 3 picks up and carries away the particles of ground material when they have been reduced to the proper degree of fineness. The turning of the table 15 by means of the shaft 9 being driven by the motor 26, carries the balls 8 around, so that the balls roll upon the grinding surfaces of the rings 6 and 17 and grind the material by crushing.

the same between the balls and the rings. In view of the fact that the balls 8 do not contact with the rings at diametrically opposite points, the balls keep turning to different positions, so that they wear evenly.

In the embodiment shown in Figs. 3, 4 and 5, the parts similar to those already described are designated by the same reference characters, and the description thereof will not be repeated. In this embodiment, the ring 6 is provided on its outside with a conically shaped portion which fits into a corresponding portion of the base 12 and keeps the ring in place. The table 15' is provided with an upper conical surface 18' upon which the balls 8 rest, instead of resting upon a removable ring as described in connection with Figs. 1 and 2. In this embodiment, a loading ring 30 is provided having a beveled lower face 31 that rests upon the balls to increase the grinding effect of the same.

In the modification shown in Figs. 6 and 7, the same general form of table and grinding ring as 15, 15' and 6, 6' are used, but the balls 8 instead of being all of the same diameter are of different diameters as better shown in Fig. 7. The advantage of this is to produce better grinding by having each successive ball trace a different path of contact on each of the tables and the ring thereby doing more effective grinding and wearing the table and ring more evenly and prevents the formation of grooves. All of the balls will wear approximately the same, so that the smaller ones only need be removed after they have worn to a certain diameter and they would be replaced by balls of the largest diameter.

The inside surfaces of the rings 6 and 6' are preferably made so as to slope downwardly and outwardly at a slight angle to the vertical. It has been found that this angle to the vertical may conveniently vary from about 5° to about 25°. The upper grinding surface 18' of the table 15' (Fig. 4), or the grinding surface 18 of the ring 17 (Fig. 2), also slopes downwardly and outwardly at an angle to the horizontal, or at a larger angle to the vertical portion than the corresponding surface of the outside grinding rings 6 or 6', so that the balls 8 rest in a wedge-shaped space between the grinding ring and the table. It has been found in practice that the slope of the upper surface of the table in Fig. 4, or corresponding ring in Fig. 2, may conveniently be from about a horizontal plane to about 45° to the horizontal. The best results are obtained when the included angle between the table and the grinding ring is between 30° to 40°. The disposition of the grinding surface of the rings 6 or 6' as described above, causes the centrifugal force on the balls 8 when they are driven to exert a pressure upon the table and thereby increase the grinding effect of the balls.

Changes and modifications may be made without departing from the spirit or scope of the invention.

I claim:

1. In a grinding mill, a grinding ring having a grinding surface sloping downwardly and outwardly, a member inside of said ring having a surface sloping downwardly and outwardly at a greater angle than the grinding surface of said ring, and balls between said ring and member. 70
2. In a grinding mill, a grinding ring having a grinding surface sloping downwardly and outwardly, a revoluble member of smaller diameter than said ring having a surface sloping downwardly and outwardly at a greater angle than the grinding surface of said ring, and balls between said ring and member. 80
3. In a grinding mill, a grinding ring having a grinding surface sloping downwardly and outwardly, a revoluble member of smaller diameter than said ring having a surface sloping downwardly and outwardly at a greater angle than the grinding surface of said ring, said member being circular and coaxial with 90 said ring, and balls between said ring and member. 95
4. In a grinding mill, a grinding ring having a grinding surface sloping downwardly and outwardly, a revoluble member of smaller diameter than said ring having a surface sloping downwardly and outwardly at a greater angle than the grinding surface of said ring, said ring and member being revoluble and adjustable relative to each other, and balls between said ring and member. 100
5. In a grinding mill, a grinding ring having a grinding surface sloping downwardly and outwardly, a revoluble member of smaller diameter than said ring having a surface sloping downwardly and outwardly at a greater angle than the grinding surface of said ring, means to vary the distance between said ring and member, and balls between said ring and member. 105
6. In a grinding mill, a horizontally disposed ball supporting table having a downwardly sloping surface, balls supported on said surface, a ring outside of said surface having a surface sloping downwardly in a more nearly vertical plane than the downwardly sloping surface of said table, and means to revolve said table. 115
7. In a grinding mill, a horizontally disposed ball supporting table having a downwardly sloping surface, balls supported on said surface, a ring outside of said surface having a downwardly sloping surface, the downwardly sloping surfaces of said table and ring making an acute angle with each other, and means to revolve said table. 120
8. In a grinding mill, a circular revoluble table, a grinding ring, and balls between said table and ring, said ring having a surface to cause the centrifugal force of said balls to 125
- 130

exert pressure upon said table when it revolves.

9. In a grinding mill, a stationary grinding ring having its grinding surface sloping downwardly and outwardly, a rotor having a downwardly and outwardly sloping surface, and a plurality of grinding balls between said surfaces resting against said rotor surface and driven thereby in contact with the grinding surface of said ring.

10. In a grinding mill, a horizontally disposed ball supporting table having a downwardly sloping surface, balls supported on said surface, a ring outside of said surface having a downwardly sloping surface, the angle between said downwardly sloping surfaces being between about 20° and 70° , and means to revolve the table.

11. In a grinding mill, a horizontally disposed ball supporting table having a downwardly sloping surface, balls supported on said surface, a ring outside of said surface, having a downwardly sloping surface, the angle between said downwardly sloping surfaces being between about 30° and 40° .

12. In a grinding mill, a stationary grinding ring having its grinding surface sloping downwardly and outwardly at an angle of about 15° to the vertical, a rotor having a surface sloping downwardly and outwardly at an angle of about 45° to the vertical, a plurality of grinding balls between said surfaces resting against said rotor surface and driven thereby in contact with the grinding surface of said ring.

13. In a grinding mill, a grinding ring having a grinding surface sloping downwardly and outwardly, a member inside of said ring having a surface sloping downwardly and outwardly at a greater angle than the grinding surface of said ring, and balls of different sizes between said ring and member.

RALPH M. HARDGROVE.
